UNITED STATES PATENT OFFICE.

JOSEPH S. KINKEAD, OF TRAER, IOWA.

WINDOW-VENTILATOR.

1,078,860.

Specification of Letters Patent. Patented Nov. 18, 1913.

Application filed December 28, 1911. Serial No. 668,221.

To all whom it may concern:

Be it known that I, JOSEPH S. KINKEAD, citizen of the United States, residing at Traer, in the county of Tama and State of Iowa, have invented certain new and useful Improvements in Window-Ventilators, of which the following is a specification.

This invention relates to improvements in window ventilators of the class adapted to be arranged in a window opening to prevent direct draft through the window and likewise excluding rain and snow, and has for one of its objects to provide a simply constructed device which may be readily adapted to windows of different widths without structural change either in the window or the improved device and which does not interfere with the raising and lowering of the sash.

Another object of the invention is to provide a simply constructed device of this character which may be folded into a relatively small space when not in use.

With these and other objects in view, the invention consists in certain novel features of construction as hereafter shown and described, and then specifically pointed out in the claim, and in the drawings illustrative of the preferred embodiment of the invention—

Figure 1 is a perspective view of a portion of a window including the casing, stool or sill, and a portion of the lower sash, with the improved device attached; Fig. 2 is a transverse section on the line 2—2 of Fig. 1.

Corresponding and like parts are referred to in the following description and indicated in all the views of the drawings by the same reference characters.

The improved device may be applied to windows of various widths and windows having various forms of construction of the frames and casings, and in the drawings a portion of a conventional window is shown, the frame being indicated at 10, the stool at 11, the casing at 12, the inside stop at 13, the parting stop at 14 and the lower sash at 15, these parts being of the usual construction.

The improved device comprises a body formed of two plates 16—17 arranged to slide one over the other and preferably bent obliquely to the plane of the plates at one edge as shown at 18—19. One of the plates, for instance the plate 16, is folded over at

its lower edge as shown at 20 to form a guideway for the lower edge of the other plate, as for instance the plate 17. By this means the two plates are slidably engaged and retained in the same relative position at all points of their movement. For the purpose of this description the plate 16 will be referred to as the outer plate and the plate 17 as the inner plate. The inner plate 17 is provided with a housing or guideway 21, while the outer plate 16 is provided with a rod 22 connected at one end at 23 to the plate 16 and slidably engaging in the housing 21. By this means the two plates are held in position and prevented from lateral displacement. The folded-over portion 20 of the plate 16 is extended to form a lip 35 to bear over the edge of the stool 11 and form a guard to prevent rain and snow from "backing up" over the stool. This is an important feature of the device and adds materially to its value and efficiency.

Formed upon the outer end of the plate 16 are hinge members with which hinge members 25 on an angular plate 26 engage, the hinge members being connected by a pintle rod 27. The plate 17 is provided at its outer end with hinge members 28 having a pintle 29 and with which hinge members on an angular plate 31 engage, the two plates 25 and 31 being precisely alike. The plates 26—31 are provided respectively with screw-receiving apertures 32 each having a laterally reduced extension. The plates 26—31 are designed to bear against the confronting faces of the inside stops with the depending lip 35 of the plate 16 bearing over the edge of the stool as before stated. Holding screws or pins 34 are inserted in the frame 10 in position to receive the apertures 32 and thus hold the device in position, and no other fastening means are required. The holding means 34 are preferably headed screws or pins, and the apertures 32 are designed to pass over the head while the shank of the screws or pins will enter the reduced portions, and thus effectually lock the device to the window frame. Two of the apertures will preferably be employed in each end plate and two screws in each inside stop, to insure the steadiness of the coupling between the parts. To remove the device it will be obvious that it will be necessary simply to elevate the device until the enlarged heads of the screws or pins come opposite the apertures 32, when the plates 26—31 may be

moved inwardly upon their hinges and the device detached. When this is done the plates 26-31 may be folded against the plates 16-17, and the latter moved inwardly upon the rod 22 to dispose the device in folded position.

It will thus be obvious that a simply constructed device is produced, which may be readily extended to any desired length with-
10 in the range of the rod 22 and its housing 21 to adapt the device to windows of varying widths, and then to be collapsed into relatively small spaces when not required.

The plates 16-17 may be constructed of
15 any suitable material, but will preferably be of sheet metal, and may be painted, plated, or otherwise protected or ornamented as required. The plates may be painted or stained to correspond to the window casings
20 and frames, so that they will not present an objectionable appearance. The plates 16-17 it will be noted, stand at an outwardly and downwardly inclined position so that any
25 rain or snow which may be driven against the plates will fall downwardly and outwardly over the sill and not enter the room.

The device is simple in construction, can

be produced at a small cost and is strong and durable and easy and convenient to adjust and apply and to remove from the window. 30

Having thus described the invention, what is claimed as new is:

In a device of the class described, body members slidably disposed with respect to each other, said members having their upper edges offset and disposed to overlap whereby the members are guided in their sliding movement, the lower edge of one of the members being turned over to embrace the lower edge of the other member, a housing 35 mounted upon one of said members at its transverse center, a rod connected at one end to the other member and slidably engaging in said housing, end members hing- 40 edly connected respectively to said body members, and means for coupling said end members to a window.

In testimony whereof I affix my signature in presence of two witnesses.

JOSEPH S. KINKEAD. [L.S.]
